[57] CLAIM

The ornamental design for a housing for telephones or
the like, substantially as shown and described.

DESCRIPTION

FIG. 1 is a perspective view of a housing for telephones
or the like showing my new design;

FIG. 2 is a top plan view of FIG. 1;

FIG. 3 is a bottom plan view of FIG. 1, the surface
being essentially flat;

FIG. 4 is a side elevational view taken from the right of
FIG. 1;

FIG. 5 is a side elevational view taken from the left of
FIG. 1;

FIG. 6 is a front elevational view of FIG. 1;

FIG. 7 is a rear elevational view of FIG. 1;

FIG. 8 is a side elevational view of a second embodi-
ment of the design of FIG. 1, similar to FIG. 4; the only

difference being the triangular windows in the sides;

FIG. 9 is a side elevational view of the second embodi-
ment, similar to FIG. 5.
